AIRSHIP

Application filed March 12, 1930, Serial No. 435,276, and in Germany March 18, 1929.

My invention relates to airships, that is lighter-than-air craft, and has special reference to ships of this kind which have a rigid hull. Such rigid airships have gas cells within 5 their hull and an outer cover stretched over it.

As these ships from year to year are designed and constructed in constantly increasing dimensions, it is one object of my invention to provide for a strong hull structure and yet to make use of every space available for inflating it with weight carrying lifting gas, such as helium or hydrogen for example.

For this purpose I provide two normal hull structures each consisting of longitudinal members and of cross members one within the other and connect them by force transmitting elements such as struts, wires, cables and the like, which are also adapted to hold both hull structures at the predetermined distance. These connecting elements, according to my invention, are so arranged that chamber-like spaces are formed between both hull structures, and into these chambers additional gas cells are inserted which give additional lift to the extremely strong rigid airship.

In certain cases it may be advisable to provide different kinds of gas in the different gas cells. For example the outer cells may be inflated with helium and the normal inner cells with hydrogen, or vice versa. Or special compartments may be filled with one gas and others with other gas.

As fuel gas is now used with airships certain compartments may serve as fuel gas containers, whilst others may be filled with lifting gas.

The manner of distributing the different gases within the airship is not subject of my present invention, but my new way of constructing the double hull structure opens new and advantageous possibilities for such distribution.

According to my invention the inner gas cells may also be in connection with one or more of the outer cells by means of connecting gas channels; or the outer cells may simply form bays forming part of the inner

cells; or the outer cells may be interconnected by channels in any suitable manner.

Having given a general description of my invention I now want to point it out more in detail referring to the drawing which represents an example embodying my invention.

Fig. 1 is a longitudinal vertical section through the hull of a rigid airship. Fig. 2 is a cross section taken on line 2—2 of Fig. 1, but on an enlarged scale. Fig. 3 is a middle portion of the hull of the airship in longitudinal vertical section like Fig. 1, but on the same scale as Fig. 2.

In Fig. 1 merely the hull structure is pointed out, whereas Figures 2 and 3 show the gas cells also, partly broken up.

The outer hull is indicated at *a*, the inner one at *b*. There are connecting struts *c* and bracings *m* provided between them. *d* and *e*, respectively, are the longitudinal girders of the outer and inner hull, respectively. The corresponding cross or ring girders are indicated by the letters *f* and *g*, respectively. Thus there are chambers provided between the two hulls into which gas cells *h* are inserted. The inner gas cells *i* are connected to the outer cells *h* by channels *l*, whereas the outer cells themselves are interconnected by channels *k*.

In the example shown the two hulls are equally distanced from each other; but, of course, under certain conditions it may be preferable to have the distance vary, for example to have a smaller distance in the upper part of the ship and to have a wider distance and stronger construction in its lower part.

I do not want to be limited to the details described or shown in the drawing as many variations will occur to those skilled in the art.

What I claim is:

1. A rigid airship comprising an outer hull structure, an inner hull structure, a structure connecting said outer hull to said inner hull, a gas cell within said inner hull, two gas cells within the space between said outer hull and said inner hull, and connecting means between said latter two gas cells.

2. A rigid airship comprising an outer hull structure, an inner hull structure, a structure connecting said outer hull to said inner hull, a gas cell within said inner hull,
- 5 a gas cell within the space between said outer hull and said inner hull, and connecting means between said two gas cells.
- 10 3. An airship including an independent hull structure comprising transversely extending polygonal rings secured together by longitudinally extending members, and a second independent hull structure surrounding the first and comprising transversely extending polygonal rings connected together by a
- 15 second group of longitudinally extending members, means connecting and holding the hull structures in spaced relation, gas cells within the first hull structure, and gas cells between the first and second hull structures.
